SPRING

Osmun W. Lorini, Yonkers, N. Y.

Application November 28, 1939, Serial No. 306,456

3 Claims. (Cl. 267—1)

This invention relates to an improvement in spring constructions, and has for one of its objects the provision of springs so constructed that their action is controlled thereby providing an arrangement having numerous uses. My construction is such that the action of the spring is delayed; in other words, the construction is such that sudden motion, as in an ordinary spring, is resisted, the spring, after distortion, returning to its initial shape slowly and uniformly.

More specifically my invention comprehends the provision of a spring which is combined with a retarding material in such a fashion that the sudden return of a distorted spring to its initial shape is resisted, with the result that the action of the spring is slow and uniform. By properly proportioning the retarding material to the spring material one may obtain a spring which instead of restoring itself instantly to initial shape may take several hours to operate.

Such a construction is useful, for example, in time switches or other type of delayed action mechanism where more expensive equipment such as dashpots, clock mechanisms, etc. are now used.

I find that fiber, copper, lead, tin and various other materials may be used, with good results, in the practice of my invention, as well as alloys of some of these materials. For example, an alloy composed of lead and tin gives excellent results, in so far as uniformity of action and long life are concerned. The inherent resistance of an alloy of lead and tin, say from 30% to 50% tin, to return of a spring to its initial shape is such that comparatively little energy is consumed in overcoming it so that the spring starts in motion, leaving considerable spring energy available for useful work.

Aside from the theory as to why my construction functions as it does, I provide a spring with which a retarding material is so combined that sudden movement of the spring after distortion tending to restore it to its original shape is resisted and controlled.

In the accompanying drawing I have illustrated several embodiments of my invention:

Figs. 1 and 2 show my invention applied to helical coil springs;

Figs. 3, 4 and 5 show my invention applied to helical springs which are to be deflected, the spring after deflection slowly returning to its original shape;

Fig. 4 is a section on the line 4—4 of Fig. 3;

Figs. 6, 7, 8 and 9 illustrate my invention applied to a flat spring;

Fig. 7 is a section on the line 7—7 of Fig. 6; Fig. 10 illustrates another embodiment of my invention as applied to a helical extension spring; Figs. 11 and 12 illustrate my invention as incorporated in spiral springs; and Figs. 13 and 14 illustrate the application of my invention to torsion springs.

Referring to the drawing in detail and first of all to the embodiment of my invention as illustrated in Fig. 1: In this figure I have shown a helical coil spring 2 enclosed in a helical tube 4 of retarding material such as above mentioned. The wall thickness of the alloy tube will depend upon the desired action of the assembly, the slower the desired action of the spring, the thicker the wall of the alloy tube. As explained above, the return of this spring assembly to initial shape is slow and uniform.

In Fig. 2 I have shown a construction which is the same in principle as the embodiment of the invention of Fig. 1. In this construction the spring 6 is hollow and within helices of this hollow spring is a helix 8 of the retarding material above referred to. When the hollow spring member 6 is compressed or extended its return to its original shape is resisted by the hollow member or helix 8, as now will be understood.

Figs. 3 and 4, Fig. 4 being a section, on the line 4—4 of Fig. 3, illustrate another application of my invention. This form of my invention is directed to the control of a helical spring which is to be distorted by bending, as distinguished from the torsional distortion of the springs of Figs. 1 and 2. The helical spring of these two figures is designated 10, and this spring is wrapped helically about a bar or rod 12 of any of the retarding materials referred to. It will be quite apparent that where this spring assembly is deflected or bent to the shape shown in Fig. 3 by the application of force thereto transverse of the axis of the spring and is released, instead of snapping back to its original shape, it will return to initial shape very slowly, retarded by the bar 12.

Fig. 5 shows a reversal of parts as compared with Fig. 3, the helically wound spring designated 14 extending through the bore of a tube 16 of retarding material.

Figs. 6 and 7, 8 and 9 show still further embodiments of the invention. With respect to Figs. 6 and 7, Fig. 7 being a section on the line 7—7 of Fig. 6, it will be seen that 18 represents a flat spring, bent to a U-shape, a rod 20 passing through its free ends. This rod is provided with limiting stops 22. Superimposed on this

spring is a retarding strip 24, riveted to the spring at 26, or otherwise secured to it, the other end of the strip 24 passing through a band 28 carried by the spring. When the spring is deflected so as to move the free ends toward each other and then released, the return of the spring to its original shape will be slow and uniform, as compared with a snap action, due to the resistance offered by the retarding strip 24.

Fig. 8 shows in cross section the same design as Figs. 6 and 7, except that a strip 24' is employed having a cross-section differing from that of Fig. 6.

In Fig. 9 the spring 18 is enclosed in a tube 24" of retarding material.

Still another embodiment of my invention has been illustrated in Fig. 10. Referring to this figure of the drawing, 30 designates a rod mounted in fixed support 32. A coil spring 34 is mounted on this rod. 36 is a stop on the rod adjacent one end of the spring 34, while 38 is an adjustment nut at the other end of the spring for adjusting the tension of the spring. 40 designates a retarding strip anchored at one end to a fixed member 42. The strip 40 is bent or bowed, its free end being received by the rod 30, and lying between the stop 36 and the end of the spring 34. By applying pressure to the free end of the retarding strip 40 the spring 34 may be compressed, and when this pressure is removed the spring will return to its original shape with a slow uniform movement resisted by the strip 40, instead of with a snap action.

Figs. 11 and 12 show the application of my invention to spiral springs. In Fig. 11, 44 designates a spiral spring, its inner end being secured to a member 46 to be rotated. Extending along the outside of this spring in Fig. 11 is a retarding strip 48, the inner end of which is secured to the member 46, its outer end being attached to the outer end of the spring, as seen at 50. Unwinding of this spring, as will be apparent, is slow and uniform, due to the resistance of the retarding strip 48.

In Fig. 12 I illustrate a similar construction except that the strip 48' is on the inside of the spring 44', instead of along the outside, as in Fig. 11.

Figs. 13 and 14 illustrate applications of my invention to torsion members. In Fig. 13, spring metal bar or rod 52 passes through a tube 54 of retarding material. The bar and tube are connected to each other by bending their ends, as illustrated. When the bar 52 is twisted and released, its return to its original shape is resisted by the tube 54, as will be understood, so that its return will be slow and uniform.

Fig. 14 illustrates the same idea, 56 being a tube of spring metal through which passes a rod 58 of retarding material. The tube and rod are bent at the ends, as before, and when the spring metal tube is twisted and released its return to normal is resisted by the bar 58.

It will be apparent from all of the foregoing that my invention provides a spring construction in which the return of the spring to its initial shape after distortion is slow and uniform, instead of the snap action of the usual spring. While I have illustrated several embodiments of my invention, it is to be understood that I have not attempted to exhaust the possibilities of my invention in this respect, the invention being capable of incorporation in other forms within the purview of my invention.

What I claim is:

1. A spring construction comprising in combination a spring wound in torsion and an inelastic retarding element for controlling the unwinding of the spring, the retarding element intermediate its ends being free of attachment to the spring.

2. A spring construction comprising in combination a spring wound in torsion and a lead tin alloy retarding member therefor, the spring and retarding member being free of attachment to each other intermediate their ends, one end of the retarding member being so connected to the spring that unwinding of the spring is controlled.

3. A spring construction comprising in combination a coil spring wound in torsion and a lead tin alloy coil connected at one end to the spring but otherwise free of attachment thereto, for controlling unwinding of the spring.

OSMUN W. LORINI.
